GEARBOX FOR BOTTLE CLEANING
MACHINES

George J. Meyer, Milwaukee, Wis., assignor to
Geo. J. Meyer Manufacturing Co., Cudahy,
Wis., a corporation of Wisconsin

Application January 23, 1943, Serial No. 473,305

9 Claims. (Cl. 285—97.7)

The present invention relates to bottle cleaning machines and more particularly to spindle-driving gear-boxes for such machines.

In a usual type of bottle cleaning machine, such as that shown in Patent No. 1,429,960 to George J. Meyer, dated September 26, 1922, bottles are carried in a conveyer and while inverted are subjected to various cleaning operations including an inside brushing operation by means of hollow brush spindles which conduct washing water into the bottles. A bottle cleaning machine of this general type is also shown in Patent No. 1,310,128 to George J. Meyer, dated July 15, 1919.

An object of the invention is to provide an improved spindle-driving gear-box which will insure adequate lubrication of the parts, which will avoid contamination of the spindle-conducted cleaning water by the lubricant for the gear-box, which will require only infrequent attention to replenish lubricant, and which will be efficient in operation.

Another object of the invention is to provide a gear-box which is of relatively simple construction and which can be economically manufactured.

A further object is to provide a gear-box in which the rotating parts have a relatively large bearing area in a limited space.

The invention further consists in the several features hereinafter described and claimed.

In the accompanying drawing,

Fig. 1 is a top view of a gear-box constructed in accordance with the invention, parts being broken away, parts being shown in section, and parts being omitted;

Fig. 2 is a transverse sectional elevation of the gear-box, taken generally along the line 2—2 of Fig. 1;

Fig. 3 is a longitudinal sectional elevation, taken generally along the line 3—3 of Fig. 1;

Fig. 4 is a transverse sectional elevation, taken generally along the line 4—4 of Fig. 1;

Fig. 5 is an elevation of a spindle housing member, and

Fig. 6 is a bottom view of the spindle housing member, parts being broken away and parts being shown in section.

In the drawing, 15 designates the main frame of a bottle cleaning machine which may be such as that shown in the above-identified Patent 1,429,960, and 16 designates the rows of bottle holders of the bottle conveyer thereof by the movement of which the rows of inverted bottles 17 are successively brought into position to receive various cleaning operations, as is well un-

derstood in this art. These operations include an inside brushing operation by fountain brush mechanism 18 here shown to comprise two transversely extending rows of tubular brush spindles 19 carried in upstanding position on a gear-box designated generally by 20. This gear-box, with which the present invention is concerned, and which is hereinafter more fully described, forms a reciprocating support or cross-head slidable on vertical guide bars 21 disposed at the opposite sides of the machine. The tubular brush spindles 19 pass through the usual tubular guides 22 which form bottle-centering clamps, and are provided with brushes 23 at their apertured upper ends adapted to enter the inverted bottles. The conduit-forming brush spindles are supplied with water or other cleaning fluid under pressure, as hereinafter described.

The gear-box 20 includes an elongated rectangular casing member 24 having opposite vertical side walls 25 and vertical end walls 26 and further having inturned top and bottom flanges 27 and 28, respectively. The casing member is preferably constructed of metal plates welded together, but it may also be formed as a casting. Cast metal end members or heads 29 and 30 are rigidly bolted to the opposite end walls 26 of the casing member and carry slide shoes 31 engageable with the side guides 21 of the machine. The end members 29 and 30 are provided with aligned horizontal tubular bearing portions 32 the inner ends of which extend through apertures 33, Figs. 2 and 3, formed in the casing member end walls 26, each bearing portion having a surrounding flange 34 which is bolted to the outer face of the respective end wall. A drive shaft 35 is journaled in the aligned bearing portions of the casing end members and carries a drive pulley 36 at one end. Suitable lubricant seals 37 surround the shaft at the outer ends of the bearing portions 32. The gear-box is raised and lowered by the usual lever and link mechanism 38, only parts of which are shown.

The top of the casing member 24 is closed by a plurality of spindle housing members 39, two being shown in the present instance. Each housing member has a plate-like top wall 40 the opposite side edges of which are bolted or secured to the top flanges 21 of the casing member. An end edge of one housing member is attached by screws 41 to one end of the casing member, these screws also securing a fastening strip or plate 42 which is attached by screws 43 to the top wall of the end members 29. The opposite edge of the housing member has an upwardly offset flange 44

which overlaps an edge of the top wall of the other housing member and is secured thereto by screws 45. The upwardly offset edge flange 44 of the second housing member similarly overlaps a flanged portion of the top wall of the casing end member 30 and is secured thereto by studs 46, these studs also securing the end member to the top flange 27 of the casing member 24.

The bottom of the casing member is closed by a cover plate 47 which forms a water manifold or chamber, the opposite side edges of the cover plate being bolted or screwed to the bottom flanges 28 of the casing member. An end edge of the cover plate is attached by screws 48 to one end of the casing member, these screws also securing a fastening plate or strip 49 which is attached by screws 50 to the bottom wall of the end member 29. The other end edge of the bottom cover plate has a downwardly offset flange 51 which laps a flanged portion of the bottom wall of the end member 30 and is secured thereto by screws 52, these screws also securing the end member to the bottom flange 28 of the casing member. The bottom cover plate 47 is formed with two longitudinally extending water passages 53 which receive water from a transverse connecting inlet passage 54, this passage being supplied with water from a conduit 55.

Each spindle housing member 39 is integrally provided with a group of four tubular bearing portions or sleeves 56 which extend vertically above and below the top wall 40, and is further provided with tubular bearing portions 57 extending in alignment with the respective bearing portions 56 and spaced downwardly therefrom to admit gearing hereinafter described. The lower ends of the bearing portions 56 are connected by a flat horizontal ring-like web 58, and the upper ends of the bearing portions 57 are connected by a similar web 59, these webs being connected by vertical webs 60, and the upper web 58, being connected to the housing wall 40 by vertical webs 61, thus providing a rigid structure. The lower ends of the bearing portions 57 are formed with flanged feet 62 which are secured to the bottom cover plate 47 by bolts 63. Central water ports 64 are formed in the lower ends of the bearing portions 57 and register with ports 65 formed in the bottom cover plate and communicating with the water passages 53.

A tubular spindle shaft 66 is journalled in each bearing portion 56 and in its lower extension 57, and has a screw-threaded upper end 67 projecting above the bearing portion 56. A pinion or gear 68 is pressed onto the shouldered intermediate portion of the tubular spindle shaft and occupies the space between the upper and lower bearing portions, the gear resting on the enlarged flat upper end 69 of the bearing portion 57. A water pipe 70 extends coaxially within the tubular spindle shaft 66 in spaced relation to the inner walls of the shaft and has its lower end screw-threaded at 71 into the bottom portion of the lower bearing sleeve 57 to communicate with the water port 64. The upper end of the pipe 70 extends above the upper end of the tubular shaft and is provided with a bushing 72. A coupling nut 73 has a skirted lower end 74 screw-threaded onto the upper end of the shaft 66 and has its upper end formed with a polygonal socket 75 to receive therein the laterally flattened bulbous lower end 76 of the corresponding brush tube or spindle 19 to form a driving connection therewith. The bulbous tube end 76 is retained in the coupling nut by a screw-threaded cap 77,

there being suitable packing washers 78 above and below the tube end. The brush tube is thus capable of a slight angular displacement with respect to the coupling nut, and is readily replaced if renewal becomes necessary. A tubular stem or nipple 79, formed of Monel metal or other suitable material, is swaged or otherwise rigidly secured in the coupling nut to form a coaxial water passage therein and has its lower end snugly but slidably and rotatably fitting in the bushed upper end of the water pipe 70. The pipe stands well above the casing member 24 and has sufficient length and resilience to accommodate any small misalignment of the pipe and nipple 79 without danger of binding and with a minimum of friction.

The pinions or gears 68 of each group of four spindles mesh with a somewhat larger spur gear 80 integrally formed on a composite gear member 81 rotatable on a vertical axis, the lower portion of the gear member also having integrally formed thereon a bevel gear 82 meshing with a bevel gear 83 carried on the drive shaft 35. Aligned upper and lower vertical shafts 84 and 85, respectively, are integrally formed on the composite gear member, the entire gear member being preferably formed of the same metal. The upper shaft is journalled in a bearing sleeve 86 integrally formed on the spindle housing member 39 and extending above and below the top wall 40, the lower end of this sleeve extending below the top plane of the spur gear 80. A step bearing member 87 for the gear member 81 is secured to the bottom cover plate 47, as by screws 88, and has a pair of upstanding coaxial bearing sleeves 89 and 90. The lower shaft 85 of the composite gear member 81 is journalled in the inner sleeve 89 of the step bearing member. The upstanding coaxial bearing sleeves 89 and 90 fit in deep annular channels 91 and 92 formed in the lower end portion of the composite gear member, thus providing a relatively large bearing area in a limited axial length. The large upper and lower bearing surfaces of the composite gear serve to minimize wear. The horizontal drive shaft 35 is also journalled in the bearing member 87. There is one bearing member 87 for each spindle housing member. All the brush spindles preferably rotate in the same direction.

The gear-box forms therein a lubricant chamber for receiving a thin fluid lubricant which will readily reach all the bearing surfaces and which will insure easy running of the rotating parts. The lubricant is of a type which will not be damaged by water and preferably consists of a cutting compound mixed with soap and water. This compound is commonly used for lubrication in metal cutting operations. If any water should accidentally leak into the gear-box, it will merely dilute the lubricant and cause no harm. The vertical water pipes 70 stand well above the lubricant level in the casing member 24 so that there is no danger of contaminating the cleaning water with the lubricant. An overflow opening 93 is formed in one of the side walls of the casing member and in some instances may be closed by a detachable plug 94. The tubular bearing portions or sleeves 56, 57, and 86 are preferably provided with openings 95 to admit the lubricant to the bearing surfaces. The lubricant reaches the bearing surfaces above the lubricant level by capillary attraction and by the splashing caused by the rotation of the gears. The bearing bushings 72 for the small diameter nipples 79 are

lubricated by the water passing upwardly through the pipes 70.

By way of example, the drawing shows four brush spindles in each row, but the number of spindles will vary according to the capacity of the machine. In some instances, as many as twenty-eight or more brush spindles may be provided in each row. In assembling any given gear-box a sufficient number of identical spindle housing members (each having four spindles) are mounted on the gear-box to provide the requisite number of spindles, thus facilitating manufacture. As seen in Fig. 3, the adjacent edges of the housing members are secured together in lapping relation. If desired, two or more bottom cover plates 47 may be secured together endwise in a similar manner for gear-boxes of different length.

In operation, the rows of inverted bottles 17 are successively brought by the conveyer into registration with the vertical brush spindles 19 in the usual manner. The gear-box 20 is then raised on the guides 21 to project the hollow brush spindles into the bottles for brushing and washing the inner surfaces of the bottles, and is then lowered to permit the succeeding rows of bottles to move into brushing position. Each bevel gear 83 on the horizontal drive shaft 35 rotates the associated composite gear member 81 which in turn rotates the corresponding group of hollow spindle shafts 66. The cleaning water passes upwardly under pressure through the non-rotatable pipes 70 from the water passages 53 in the bottom cover plate, and then through the rotating nipples 79 and brush tubes, finally discharging into the bottles.

The construction of the gear-box of the present invention is such as to permit easy but accurate machining of the parts and to facilitate assembly. Although the construction permits the use of a thin fluid lubricant to insure thorough lubrication of the moving parts and to obviate the need for individual lubricant fittings for the bearings, there is no danger of contaminating the water or other cleaning liquid passing through the brush spindles.

What I claim as new and desire to secure by Letters Patent is:

1. In a spindle mechanism for a bottle cleaning machine, the combination of a hollow support forming therein a lubricant chamber adapted to receive a fluid lubricant, a tubular spindle projecting upwardly from said support and having a portion journaled in said support and exposed to the lubricant in said chamber, a pipe secured to said support and extending upwardly within said spindle to a point above the lubricant level in said chamber, said pipe having its upper end portion interfitting with said spindle and communicating with the interior of said spindle, gearing means in said support for rotating said spindle, and means for admitting liquid to the lower end of said pipe for passage through said spindle.

2. In a spindle mechanism for a bottle cleaning machine, the combination of a hollow support forming therein a lubricant chamber adapted to receive a fluid lubricant, a tubular spindle projecting upwardly from said support and having a portion journaled in said support and exposed to the lubricant in said chamber, a resilient pipe rigidly secured at its lower end to said support and extending upwardly within said spindle in spaced relation to the inner walls of said spindle to a point above the lubricant level

in said chamber, said resilient pipe having a laterally deflectable upper end portion interfitting with said spindle and communicating with the interior of the spindle, gearing means in said support for rotating said spindle, and means for admitting liquid to the lower end of said pipe for passage through said spindle.

3. In a spindle mechanism for a bottle cleaning machine, the combination of a hollow support forming therein a chamber adapted to receive a fluid lubricant, an upwardly projecting hollow spindle shaft journaled in said support and exposed to the lubricant in said chamber, a pipe secured at its lower end to said support and extending upwardly within said shaft to a point above the lubricant level in said chamber, a spindle tube detachably secured to the upper end of said shaft and having a part slidably and rotatably interfitting with the free upper end of said pipe, gearing means in said support for rotating said spindle shaft, and means for admitting liquid to the lower end of said pipe for passage through said spindle tube.

4. In a spindle mechanism for a bottle cleaning machine, the combination of a hollow support forming therein a chamber adapted to receive a fluid lubricant, an upwardly projecting hollow spindle shaft journaled in said support and exposed to the lubricant in said chamber, a pipe secured to said support and extending upwardly within said shaft to a point above the lubricant level in said chamber, a spindle tube secured to the upper end of said shaft and having a downwardly projecting tubular stem rotatably interfitting with the free upper end of said pipe, gearing means in said support for rotating said spindle shaft, and means for admitting liquid to the lower end of said pipe for passage through said spindle tube.

5. In a spindle mechanism for a bottle cleaning machine, the combination of a casing forming therein a chamber adapted to receive a fluid lubricant, said casing having top and bottom cover members, said top cover member having a bearing portion extending downwardly into said chamber and secured to said bottom cover member, a tubular spindle journaled in said bearing portion and projecting upwardly therefrom, a pipe secured at its lower end to the lower part of said bearing portion and projecting upwardly within said spindle to a point above the lubricant level in said chamber, the free upper end of said pipe interfitting with said spindle and communicating with the interior of said spindle, gearing means in said casing for rotating said spindle, and means carried by said bottom cover member for admitting liquid to the lower end of said pipe.

6. In a spindle mechanism for a bottle cleaning machine, the combination of a casing forming therein a chamber adapted to receive a fluid lubricant, said casing having top and bottom walls, said top wall having a bearing portion extending downwardly into said chamber, there being a gap at an intermediate point of said bearing portion, a tubular liquid-conducting spindle journaled in said bearing portion and projecting upwardly therefrom, gearing means in said casing for rotating said spindle including a gear mounted on said spindle and disposed in said gap, and means for supplying liquid to said tubular spindle and for excluding lubricant from passage through said spindle.

7. In a spindle mechanism for a bottle cleaning machine, the combination of a casing form-

ing therein a chamber adapted to receive a fluid lubricant, said casing having a top wall comprising a housing plate having a plurality of laterally spaced spindle bearings formed thereon and projecting into said lubricant chamber, tubular liquid-conducting spindles journalled in said respective bearing portions and projecting upwardly therefrom, gearing means in said casing for rotating said spindles, and means for supplying liquid to said tubular spindles.

8. In a spindle mechanism for a bottle cleaning machine, the combination of a casing forming therein a chamber adapted to receive a fluid lubricant, said casing having a top wall comprising a plurality of housing plates each having a plurality of laterally spaced spindle bearings formed thereon and projecting into said lubricant chamber, said housing plates having adjacent lapping edge portions, tubular liquid-con-

ducting spindles journalled in said respective bearing portions and projecting upwardly therefrom, gearing means in said casing for rotating said spindles, and means for supplying liquid to said tubular spindles.

9. In a spindle mechanism for a bottle cleaning machine, the combination of a casing forming therein a chamber adapted to receive a fluid lubricant, said casing having top and bottom cover members, said top cover member having a bearing portion extending downwardly into said chamber, a tubular liquid-conducting spindle journalled in said bearing portion and projecting upwardly therefrom, gearing means in said casing for rotating said spindle, and means for supplying liquid to said spindle including a conduit on said bottom cover member.

GEORGE J. MEYER.
